UNITED STATES PATENT OFFICE.

WILLIAM S. HADAWAY, JR., OF NEW ROCHELLE, NEW YORK.

ELECTRIC HEATER.

Application filed December 30, 1915, Serial No. 69,334. Renewed October 27, 1921. Serial No. 510,947.

To all whom it may concern:

Be it known that I, WILLIAM S. HADAWAY, Jr., a citizen of the United States of America, and a resident of New Rochelle, 5 Westchester County, and State of New York, have invented certain new and useful Improvements in Electric Heaters, of which the following is a specification, reference being had to the accompanying drawings, 10 forming a part thereof.

My invention relates to novel means and method of producing heat for general purposes, such as the heating of a room or chamber in an office or dwelling house. It 15 has special reference to the use of electricity in conjunction with other means for producing heat.

It is a well known fact that by the combustion of suitable fuel, under proper conditions which are easily attainable, heat can be produced at a cost far below that generated electrically under the most favorable conditions available up to the present time. Nevertheless, electricity has been extensively 25 used because of many advantages too well known to need repetition. The foremost of these is probably ease of regulation and control.

One object of my invention is to provide a 30 heat generator that shall utilize electricity for starting, stopping and regulating the generation of heat by other means such as the combustion of fuel, the heat generated electrically being added to that otherwise produced but forming a relatively small percentage of the total heat generated.

Another object is to provide a heater that shall be adapted to burn solid fuel and that shall utilize electricity for starting and 40 maintaining combustion when, and to the extent necessary to produce the heat desired, whereby the standby losses usually incident to the keeping of the fire are largely avoided.

Another object of my invention is to make the electrically produced heat, the high temperature component which is a recognized essential of the combustion of coal and like fuels. In other words, the electricity produces a relatively small quantity of heat at a 45 temperature much in excess of that required as a final product for useful consumption, the high temperature heat being used for the purpose of instigating, maintaining and

controlling the combustion of the fuel which produces heat in larger quantities at relatively small cost. 55

The embodiment of my invention which I now consider preferable and which will be shown and described in detail herein, comprises a high temperature heater of the general character set forth in my copending application, Serial No. 42,933 filed July 31, 1915, which is adapted by the consumption 60 of electric energy to transform low temperature steam into intensely hot gases. It further comprises a fuel container in which the fuel is subjected to the hot gases from the high temperature heater, the rate of combustion as well as its initiation being controlled 65 in response to the regulation of the high temperature heater.

Another object of my invention is to provide a fuel combustion heater in which hot gases are utilized for starting, maintaining 70 and regulating combustion.

Another object is to provide a compact and economical combustion heater embodying means for preheating the supporter of combustion, regulating the quantity and 75 velocity thereof and separating the ash from the fuel.

Another object is to provide a heater which shall be particularly adapted to burn carbonaceous fuels such as coke from which the hydro-carbon gases and other distillates 80 have been removed.

Another object is to provide a combustion apparatus in which blocks of previously prepared fuel may be burned with a maximum 85 of convenience and economy.

Another object is to provide an automatic means for burning carbonaceous materials which have previously been pressed or ground in masses of definite dimensions and covered with paper for example, to secure 90 refinement as well as convenience in the handling of the fuel.

Another object is to develop an electric furnace which may be broadly used in the arts and in domestic service and which derives a considerable part of its heat from combustion in addition to that obtained 95 from the electrical service.

Another object is to secure ignition of fuel by preheating the oxygen carrier to so high a temperature that it combines with carbonaceous material upon which it may impinge 100

irrespective of the initial temperature of the latter.

Another object is to secure ignition of fuel by preheating the oxygen carrier by electricity or otherwise to so high a temperature that the carrier may be a vapor such as steam for example, partially dissociated.

Another object is to secure regulation and control of an electrically heated combustion apparatus, by providing the combustion chamber of its electric furnace with fire-bricks made chiefly of magnesia or of other materials which are electrical insulators at ordinary temperatures and electrical conductors at the preferable operating temperature of the furnace.

Another object is to secure regulation and control of an electric furnace by using a part of its fireproof lining as an electrical switch, that is, a conductor of electricity at high and an insulator at low temperatures.

Another object is to utilize electricity in furnace work at high temperatures without recourse to the customary low voltage electrical translating appliances.

Other objects and advantages of my invention will be set forth hereinafter, and in order that my invention may be thoroughly understood, I will now proceed to describe the same in the following specification, and then point out the novel features thereof in appended claims.

Referring to the drawings:

Figure 1 is a front elevation of an electric fuel heater arranged and constructed in accordance with my invention.

Figure 2 is a sectional plan view on the line 2-2 of Figure 5 showing a portion of the structure of Figure 1.

40 A modified structure consisting of a single unit is shown in elevation in Figure 3, which corresponds to Figure 1, and in sectional plan view in Figure 4 which corresponds to Figure 2.

45 Figure 5 is a sectional elevation, taken on the line 5-5 of Figure 1 and drawn to a larger scale.

50 Figures 6 and 7 are sectional plan views showing the structure of one of the units and are taken respectively on the lines 6-6 and 7-7 of Figure 5.

55 A diagram of the circuit connections which may be conveniently utilized for energizing and controlling the heater of my invention, is shown in Figure 8.

Like characters of reference designate corresponding parts in all the figures.

60 Referring particularly to Figures 1, 2, 5, 6 and 7, the structure here shown comprises a supporting bracket 10 which may conveniently be mounted on a wall, such as 11, in which is a flue or chimney opening 12. Mounted on the bracket are electric heater and dissociater units 13 which are preferably similar in construction to that which

forms the subject matter of my copending application Serial No. 42,933 filed July 31, 1915.

70 Mounted upon these heaters and receiving their energy therefrom, as hereinafter explained, are a plurality of fuel combustion units 14. The number of units is of no consequence to my invention and in fact, as illustrated in Figures 3 and 4, my invention may be embodied in a heating device consisting of a single unit. The units 14 are mounted, together with the electric heater and dissociater units 13, in a box or casing 15 which has a front opening 16 through which heat generated in the apparatus may be radiated, and a perforated cover 17. The body of the box may be integral with the bracket 10 as indicated in Figure 5, or the two parts may be separate and attached as desired.

80 The wall 11 is provided with a recess 18 behind the heater in which a receptacle 19 is disposed. This receptacle is preferably thin and sufficiently large to cover the entire area behind the combustion heater units, the adjacent surface of the receptacle being polished or finished to constitute a reflector for the heater. It is, of course, well known that no reflector can be provided which will absorb no heat whatsoever, and consequently, I have arranged the reflector in the form of a receptacle so that it may be filled with water to which the heat absorbed may be imparted.

90 The water has another function since the outlet pipe or flue 20 through which burnt gases from the combustion heater escape to the flue 12 may be bent into a coil 21 within the water or other cooling fluid within the receptacle. The water therefore constitutes a means for cooling the flue and preventing loss of heat which would occur if hot gases were discharged into the chimney. Furthermore, the temperature of the water is increased sufficiently so that it is evaporated rapidly and since the receptacle is open at the top and communicates with the chamber in which the heater is located, the air in the room or chamber is maintained at the proper degree of humidity for comfort and economy.

100 The heater and dissociater units 13 comprise blocks 22 or masses of heat insulating material each having a recess 23 in its upper surface, heating coils or resistors 24 embedded in the insulation, a heating coil or resistor 25 which is disposed in the recess 23, and a discharge member 26 which may be disposed within the heating coil 25. The blocks 22 may be formed integral if desired.

110 The fuel or combustion chamber 14 comprises a base ring 30 which is mounted on the insulating block 22 and has lugs or projections 31 which extend radially into the recess 23 and serve as a means for centering

the ring and holding it in position on the electric heater 13. Mounted on the projections 31 of the ring 30 is a notched ring or annular grating 32 which is preferably 5 formed of fire clay or some similar substance which is not injured by intense heat. The grating 32 constitutes a support not only for a tubular cylinder 33 of magnesia which constitutes part of each heater unit but also for 10 a cylindrical block or briquette 34 of fuel which is mounted within the tube 33.

A plurality of angle rods or bars 35 are secured to the ring 30 and extend upwardly therefrom. At their upper ends they support 15 a ring 36, the parts 30, 35, 36 together constituting a frame adapted to receive panels 37 of mica or some other suitable translucent material.

The members 30 and 36 which I have 20 described as rings, may preferably have a hexagonal form in order to avoid bending the panels, as shown in Figures 1, 6 and 7. Each unit has a cap 38 which is mounted on 25 the ring 36 and has a plurality of perforations or holes 39 through which air may be supplied to the device.

On the portion of the cap which is perforated, is a damper ring 40 which may be adjusted so as to cover a greater or less 30 number of the perforations 39.

The air supplied to the unit through these 35 openings is not relied upon as the sole oxidizing agent with which combustion is supported, but is intended rather to constitute a supplementary source of oxygen which may be readily regulated by the adjustment of the position of the damper.

The fuel block or briquette may 40 preferably be provided with a central longitudinal hole 42 through which a portion of the burnt gases may escape, the remainder passing upwardly around the exterior of the fuel block and within the magnesia tube 33.

The operation of the device is as follows: 45 Relatively low temperature steam or water vapor is supplied to the electric dissociater 13 through a supply pipe 50, the steam flowing as clearly indicated in the diagram Figure 8, through the heating coils 24 and 25 in succession and finally being broken into its constituent elements to a greater or less degree as it passes through the dissociater coil 51 and is discharged through the openings of the member 26. The temperature of 50 the discharged gases is such as to immediately start the combustion of the briquette.

The same coils which constitute steam carriers are also electric resistor elements and are referred to as heating coils. They 55 may be electrically connected in any suitable relation as indicated by the short connecting wires, Figure 8, since they are insulated from each other like those of my copending application serial No. 42,933, to which reference has already been made. The electric

energy, which may be drawn from any suitable source indicated at 52, is supplied through one blade of a double pole switch 53, conductor 54, automatic control switch 55, and coils 51, 25 and 24, to conductor 56 70 which is connected through the opposite blade of the switch 53 to one of the supply circuit conductors.

The automatic switch 55 has a magnet winding 57 which is connected across the 75 circuit in series relation with a resistance 58 and the magnesia tube 33 which forms a part of the combustion heater.

When the electric circuit is first closed, the steam becomes superheated to an increasing 80 extent as it passes through the coils 24 and 25 until finally, it is partially dissociated and is discharged at a high velocity from the small holes in the discharge member 26, in the form of a mixture of very 85 highly superheated steam and hydrogen and oxygen.

The hot gases thus discharged impinge directly upon the bottom of the fuel block or 90 briquette 34 which is a carbonaceous material and consequently unites with the oxygen and acts as a reducing agent in further promoting the dissociation of the superheated steam. The bottom and side surfaces of the briquette near the bottom are thus 95 burned, producing a large quantity of heat which gradually heats the magnesia tube 33 to a glowing temperature with the result that a large quantity of useful heat is radiated from the device. 100

The circuit above described thus comprises two branches of which one may be called the regulating branch including the resistance 58, the magnesia tube 33 and switch coil 57, and the other may be called the heating branch including the tubular vapor carrying heating coils 24, 25 and 51 and the switch 55. 105

Before the magnesia tube 33 is hot the current traversing the regulating branch is 110 not sufficient to open the switch 55 and the heating branch is therefore energized. When the magnesia tube 33 is heated to a relatively high temperature its resistance is materially reduced and the current flowing 115 therethrough and through the coil 57 is increased sufficiently to open the switch 55. Thus the heating branch is interrupted and the heating coils 24, 25 and 51 deenergized.

The temperature of the device may be 120 maintained for an indefinite time by the continued combustion of the briquette, but if the formation of ash or the like causes the temperature of the magnesia tube 33 to fall sufficiently, its resistance will be largely increased and the switch 55 will be closed on account of the corresponding reduction in the current flowing through the coil 57. The closing of the switch will again energize the electric vapor heating coils 24, 25. 125 130

When the electric vapor heaters are active, steam or hot gases at high temperatures will be forcibly discharged against the bottom of the briquette and will flow upwardly around and through the central opening in the same. By this means the temperature of the briquette will not only be increased to make the combustion again very active but also the flow of hot gases will create a powerful draft sufficient to carry away any accumulation of ash.

When the magnesia tube is at a radiant temperature and the combustion is progressing without the cooperation of the electric heaters, the switch 55 being open, the steam or relatively low temperature vapor at 212° F. for example, may be continuously delivered from the nozzle 26. The steam or water vapor coming in contact with the hot carbon will produce gas which mixes with the warm air drawn inwardly through the openings 39 and is burnt and gives up heat to the radiant body 33.

While my invention is not limited to any specific temperatures, attention is directed to the fact that I prefer to discharge the hot gases and vapor, for starting the combustion of the briquette and maintaining it under fluctuating conditions, at a high temperature, the steam being highly superheated by the electrically generated heat in the coils 24 and 25.

Furthermore, the appearance of the device, particularly the multi-unit device, shown in Figure 1, is very attractive and the space which it occupies is comparatively insignificant. It is none-the-less capable of economically consuming a relatively large quantity of carbonaceous fuel and efficiently producing heat in large quantities.

The heat is of course entirely disproportionate to the amount of electric energy utilized in the device since the electricity is only utilized to energize the furnace or burner in a sense which is comparable to the energization of the field magnets of a dynamo electric machine. In each case the average total energy output is much greater than the exciting or electrical input. In the dynamo electric machine the electricity conjunctively with the mechanical power supplied, yields an energy in which the excitation factor is but a small percentage of the total. In the case of my present invention the electricity is used conjunctively with carbonaceous or similar fuel and yields a total heat energy in which the electrical ignition and control factor is relatively small.

So far as I am aware, this introduces a comparatively new field in the electrical industry and enables the electricity at an ordinary commercial cost to be used with economy and profit both to the consumer and to the central station. My invention is furthermore, not restricted to embodiment

either in small or large units, and size, design and arrangement will depend upon the service conditions.

Attention is particularly directed to the humidifier which at the same time constitutes a means for saving the heat which would otherwise escape through the flue and for controlling the humidity of the air in the room or chamber to which the heat is supplied.

The single unit heater of Figures 3 and 4, is substantially like one of the units of the structures shown in the other figures, except that it has a single curved water receptacle 60, the outer surface of which constitutes a reflector for the unit.

Various structural modifications may be employed within the spirit and scope of my invention, and I intend that only such limitations be imposed as are indicated in the appended claims.

What I claim is:

1. Heating apparatus comprising a fuel combustion heater, and a supplemental heater comprising electrical tubular resistors adapted to be supplied with vapor and to supply high temperature vapor to fuel in the combustion heater.

2. Heating apparatus comprising a radiant heating member adapted to be heated to a glowing temperature, means for supporting combustible matter adjacent to the radiant heating member and a supplemental heater comprising electrical tubular resistors adapted to supply high temperature vapor to the combustible matter.

3. Heating apparatus comprising a member constructed to form a combustion chamber and a supplemental heater comprising vapor electric heating elements arranged to receive vapor at a relatively low temperature and to discharge gases upon fuel in said chamber at such temperature as to initiate its combustion.

4. Heating apparatus comprising a member constructed to form a combustion chamber and a supplemental heater comprising vapor electric heating elements arranged to receive vapor at a relatively low temperature and to discharge gases upon fuel in said chamber at high velocity and at such temperature as to initiate its combustion.

5. Heating apparatus comprising a member constructed to form a fuel combustion chamber and electro-responsive means for heating a carrier of oxygen prior to its ignition to a temperature required to initiate combustion of the fuel in said chamber and for discharging said heated carrier against said fuel to initiate combustion thereof.

6. Heating apparatus comprising a member constructed to form a fuel combustion chamber and electro-responsive means for heating a carrier of oxygen prior to its ignition to a temperature required to initiate

- combustion of the fuel in said chamber and for discharging said heated carrier against said fuel to initiate combustion thereof and to regulate said combustion. 65
- 5 7. Heating apparatus comprising a member constructed to form a fuel combustion chamber and electro-responsive means for heating a carrier of oxygen prior to its ignition to a temperature required to initiate combustion of the fuel in said chamber and for discharging said heated carrier against said fuel to initiate combustion thereof and to regulate said combustion, and an air inlet for the combustion chamber. 70
- 10 8. Heating apparatus comprising a member constructed to form a fuel combustion chamber, electro-responsive means for heating a carrier of oxygen prior to its ignition to a temperature required to initiate combustion of the fuel in said chamber and for discharging said heated carrier against said fuel to initiate combustion thereof and to regulate said combustion, an air inlet for the combustion chamber and means for adjusting the air inlet. 75
- 15 9. Heating apparatus comprising a member constructed to form a combustion chamber and a steam superheater arranged and adapted to initiate combustion of fuel in said chamber and to maintain the fuel at desired temperature. 80
- 20 30 10. Heating apparatus comprising a member constructed to form a combustion chamber and means for supplying either superheated gases or low temperature steam to the combustion chamber. 85
- 25 40 11. Heating apparatus comprising a member constructed to form a combustion chamber, an electro-responsive supplemental heater and means for controlling same to supply heat to initiate combustion of fuel in said chamber to maintain the fuel at desired temperature and to combine with the heat of combustion to regulate the heat generated. 90
- 35 45 50 12. Heating apparatus comprising a radiant heating member constructed to form a combustion chamber, means for introducing a vapor into said chamber, and external means for pre-heating said vapor without igniting it to a temperature above the ignition point of the fuel. 95
- 55 60 13. Heating apparatus comprising a radiant heating member constructed to form a combustion chamber, means for introducing a vapor into said chamber, and external electrical means for pre-heating said vapor without igniting it to a temperature above the ignition point of the fuel. 100
- 65 14. Heating apparatus comprising a radiant heating member constructed to form a combustion chamber and a supplemental heater for fuel in said chamber, said supplemental heater comprising electric heating elements arranged to heat a vapor prior to its ignition to a temperature above the ignition point of the fuel. 105
- 70 15. Heating apparatus comprising a heating member constructed to form a combustion chamber adapted to be heated to a relatively high temperature and constituting when hot a conductor of electricity, means for supporting fuel in position to heat said member, an electric supplemental heater for the fuel, and means dependent upon the temperature of said member for interrupting the supply of energy to the supplemental heater. 110
- 75 16. Heating apparatus comprising a member constructed to form a combustion chamber, an outer casing surrounding but spaced from said member having inlet perforations near the top and open to the combustion chamber near the bottom thereof, and a supplemental heater near the bottom of the member adapted to initiate and maintain combustion of fuel in said chamber, and maintain the fuel at desired temperature. 115
- 80 17. Heating apparatus comprising a member constructed to form a combustion chamber, an outer casing surrounding but spaced from said member having inlet perforations near the top and open to the combustion chamber near the bottom thereof, a damper for adjusting the inlet openings, and a supplemental heater near the bottom of the member adapted to initiate combustion of fuel in said chamber, and maintain the fuel at desired temperature. 120
- 85 18. Heating apparatus comprising an excitation heater forming a base, a supporting ring mounted thereon, a heating member on the supporting ring constructed to form a combustion chamber, an outer casing surrounding but spaced from said member, a cap therefor, inlet perforations near the top of the outer casing and said casing being open to the combustion chamber near the bottom thereof, a damper for adjusting the inlet openings, and a cap having an outlet flue, said excitation heater being adapted to initiate combustion of fuel in said chamber, and maintain the fuel at desired temperature. 125
- 90 19. Heating apparatus comprising an excitation heater forming a base and comprising tubular resistors adapted to be supplied with vapor and to be electrically energized, a heating member constructed to form a combustion chamber, an outer casing surrounding but spaced from said member having inlet perforations near the top and being open to the combustion chamber near the bottom thereof, a damper for adjusting the inlet openings said excitation heater being adapted to initiate combustion of fuel in said chamber, and maintain the fuel at desired temperature. 130

20. Heating apparatus comprising an excitation heater forming a base and comprising tubular resistors adapted to be supplied with vapor and to be electrically energized, a heating member constructed to form a combustion chamber, an outer casing surrounding but spaced from said member having inlet perforations near the top and being open to the combustion chamber near the bottom thereof, a damper for adjusting the inlet openings, and a cap having an outlet flue said excitation heater being adapted to initiate combustion of fuel in said chamber, and maintain the fuel at desired temperature. 55
- 5 21. Heating apparatus comprising a member constructed to form a combustion chamber, an outer casing spaced from said member and forming therewith a preheating air 60 passage, air inlet ports for the passage, means for regulating the opening of the inlet ports, and electro-responsive means for causing a carrier of oxygen to impinge against fuel in said chamber at high temperature. 65
- 10 22. Heating apparatus comprising a radiant heating member constructed to form a combustion chamber and arranged to be heated to a glowing temperature by the combustion of fuel therein, a supplemental heater for the fuel, and a translucent outer casing surrounding but spaced from said member. 70
- 15 23. Heating apparatus comprising a radiant heating member constructed to form a combustion chamber and arranged to be heated to a glowing temperature by the combustion of fuel therein, a supplemental heater for the fuel, a translucent outer casing surrounding but spaced from said member, and a cap on said casing having an outlet flue for the fuel chamber. 75
- 20 24. Heating apparatus comprising an excitation heater forming a base and comprising tubular resistors adapted to be supplied with vapor and to be electrically energized, a supporting ring mounted thereon, a radiant member on the supporting ring constructed to form a combustion chamber, an outer casing surrounding but spaced from said member having translucent portions, said casing having inlet perforations near the top and being open to the combustion chamber near the bottom thereof, a damper 80
- 25 for adjusting the inlet openings, and a cap having an outlet flue said excitation heater being adapted to initiate combustion of fuel in said chamber, and maintain the fuel at desired temperature. 85
- 30 25. The herein described method of heating which comprises heating a vapor by other means than by ignition thereof to a temperature above the ignition temperature of a fuel and applying a current of the heated vapor to the fuel. 90
- 35 26. The herein described method of heating which comprises heating a vapor by other means than by ignition thereof to a temperature above the ignition temperature of a fuel, applying a current of the heated vapor to the fuel, and admitting air to the point of combustion. 95
- 40 27. The herein described method of heating which comprises heating a vapor to a temperature above the ignition temperature of a fuel confining a body of the fuel, directing the heated vapor to the fuel, and regulating the heat generated by automatically reducing the temperature of the vapor. 100
- 45 28. Heating apparatus comprising a member constructed to form a fuel combustion chamber and means for heating a carrier of oxygen prior to its ignition to a temperature required to initiate combustion of the fuel in said chamber and for discharging said heated carrier against fuel in said chamber to initiate combustion thereof. 105
- 50 29. Heating apparatus comprising a member constructed to form a fuel combustion chamber, means for heating gases or low temperature steam prior to their ignition to a temperature required to initiate combustion in said chamber, and for discharging said heated gases or steam against fuel in said chamber to initiate combustion thereof. 110
- 55 30. Heating apparatus comprising a member constructed to form a combustion chamber, a supplemental heater, and means for controlling said heater to supply heat to initiate combustion of fuel in said chamber to maintain the fuel at a desired temperature and to combine with the heat of combustion to regulate the heat generated. 115
- 60 In witness whereof, I have hereunto set 105
my hand this 27th day of December, 1915.

WILLIAM S. HADAWAY, JR.
